UNITED STATES PATENT OFFICE.

THOMAS J. MCTIGHE, OF NEW YORK, N. Y.

METHOD OF COOLING GASES.

SPECIFICATION forming part of Letters Patent No. 650,608, dated May 29, 1900.

Application filed August 30, 1899. Serial No. 728,979. (No specimens.)

To all whom it may concern:

Be it known that I, THOMAS J. MCTIGHE, a citizen of the United States, and a resident of New York, in the county of New York and State of New York, have invented certain new and useful Improvements in Methods of Cooling Gases, of which the following is a specification.

This invention has for its object the cooling of gases either for the production of a refrigerating effect or for the liquefaction of gas.

The invention consists, briefly, in causing a compressed gas to act expansively in elevating within a heat-insulated tube a suitable liquid cooler than itself, thereby doing work and falling in temperature in proportion to the work done.

The invention further consists in utilizing the energy of position thus attained by the liquid by causing it to descend by gravity and actuate a suitable motor which is geared to mechanism for performance of work.

The invention further consists in the various processes and combinations of steps, all substantially as hereinafter fully described, and set forth in the claims.

It is well known, as illustrated by the familiar Sprengel or Geissler pump for exhausting lamp-bulbs and other apparatus, that a falling column of mercury or other liquid causes the withdrawal of portions of air from the bulb or apparatus, the dropping of the mercury continuously drawing air and the glass fall-tube exhibiting an alternation of mercury and air, each being separated from the other in more or less regular sections and each filling the diameter of the tube. I reverse these relations, and instead of a series of moving bodies of liquid pulling with them a like series of bodies of gas I place the gas under compression and cause it to expand and push upwardly a series of bodies of any desired liquid. An important principle of thermodynamics is thus brought into play. It is known that a compressed gas when allowed to expand through a small aperture loses some of its heat in the operation; but the reduction of temperature is very slight. On the other hand, it is also well known that if a compressed gas be caused to expand and do work while expanding, such as moving the piston of an engine, a very great reduction

of temperature is obtainable, only limited by the mechanical difficulties of lubrication and escape of the chilled gas. Of these two methods of cooling a gas the latter is by far the more efficient, theoretically; but the former has been most generally adopted in liquefaction processes, owing chiefly to the above difficulties, the absence of moving parts, and the resulting simplicity of apparatus; but by the adoption of my invention I am enabled to obtain the maximum thermodynamic efficiency of conversion of heat into work, the same as though I were expanding the gas against the piston of an engine, without being obliged to employ moving mechanism. I cause the compressed gas to enter the lower end of a tube submerged in a suitable liquid and push such liquid up the tube, the gas expanding continuously as it rises until it emerges at atmospheric pressure—that is to say, the gas has done mechanical work and by thus parting with energy has become lowered in temperature.

More particularly, my invention will be understood by reference to the accompanying drawing, which forms part of this specification, wherein the figure is a diagrammatic illustration, partly sectional, of an apparatus embodying the principles of my invention.

A is a stand-pipe surrounded by a suitable jacketing to prevent the undue passage of heat inwardly from the surrounding atmosphere. The stand-pipe A ends at its top in a separating-chamber B. From the latter two pipes (also heat-insulated) descend; the pipe C from near the bottom of the chamber and the pipe D from near the top of the chamber.

The stand-pipe A terminates below in a reservoir E and is preferably bell-mouthed, as shown. The liquid-pipe C has connected into it near its lower end a suitable hydraulic motor F—such, for example, as a turbine wheel—the discharge-pipe from which enters the reservoir E. The shaft of such motor may be geared to any sort of work-absorber; but I show it preferably belted to the compressor G. The pipe D receives the expanded gas from chamber B and conducts it down to the intercooler H, after flowing through which the expanded gas passes over by the pipe I to the compressor to be again compressed.

From the compressor the gas passes by pipe *k* to and through the cooler *L* and from it by pipe *m* to and through the intercooler *H*, leaving which the pipe *M* terminates in the 5 upturned nozzle *n* within the reservoir *E* and under the stand-pipe *A*. One or more stop-cocks may be applied, if desired, at suitable points; but they are unnecessary.

An upwardly-closing check-valve may, if 10 desired, be applied to the bottom of pipe *C*.

The reservoir *E*, stand-pipe *A*, chamber *B*, and hydraulic pipe *C* being primed with the proper quantity of liquid at a low temperature, the compressor is set going. The heat 15 of compression is first absorbed by the ordinary cooler *L*, which contains water or other suitable cooling agent. Thence the cooled gas passes on under pressure to the nozzle *n*, from which it rises in a continuous succession 20 of bubbles into and up the pipe *A*. Each bubble of gas pushes ahead of it a portion of the liquid which is in the reservoir, and, as in the Sprengel air-pump, the two retain their 25 separate character, each filling the diameter of the pipe *A*. Each section or bubble of gas, however, begins at once to exert its expansive power and expands more and more as it pushes the body of liquid ahead of it up the pipe *A* until with due proportioning of the 30 height to the initial presence of the gas and the density of the liquid used the latter is ejected from the pipe *A* into chamber *B*, and the now more or less completely expanded gas follows it. This action is repeated by 35 further quantities of gas and liquid in rapid succession. The gas from which the heat of compression has been removed has now had a large amount of its intrinsic heat energy converted into work, and it has fallen to a 40 very low temperature. The liquid gravitates down the pipe *C*, and by means of the motor *F* the gravitational energy of the liquid passes off in the form of work externally instead of becoming converted into heat and is discharged into the reservoir at its normal 45 temperature to be again elevated and made the means of conversion of heat into work. The cooled gas passes from the chamber *B* down the pipe *D* and through the intercooler *H*, 50 where by contact with the pipe *m* it absorbs heat from the compressed gas coming from the compressor, lowering the temperature of such gas, and this now entering the stand-pipe at a temperature lower than in the preceding cycle suffers a greater fall of temperature 55 ature by its expansion in pipe *A*.

For mere refrigerating or ice-making purposes it is sufficient to pass compressed air once through the above cycle and utilize the 60 chilled air directly from chamber *B* without using the intercooler *H*. For liquefaction purposes, however, I propose to prime the apparatus with the liquefied gas and repeat the cycle continuously. The chilling is thus very 65 rapidly effected, since not only is there a self-intensive effect produced in succeeding cycles by the gas coming from chamber *D* be-

ing used over after passing the intercooler, but there is a direct cooling due to the contact of the gas with its own liquid form in the 70 stand-pipe and a further cooling effect due to the evaporation on the surfaces of the liquid. The action is so rapid and reduction of temperature so great that a gas can be liquefied very copiously. The surplus gathers in 75 the reservoir *E*, whence it can be drawn off by the faucet *p*. To make up for the gas thus liquefied, more gas can be supplied at the filtering-funnel *s* as needed.

If air be under treatment, the action of the 80 funnel *s* is automatic, since the spent air in pipe *i* is approximately down to atmospheric pressure and the compressor will draw in at what is wanting in pipe *i*.

For refrigeration of air for ice-making purposes, &c., the priming liquid can be a mixture of salt and water or glycerin and water or other mixture, so that the gas may, if desired, be carried down to a temperature much below 32° Fahrenheit. 85

Having described my invention, I claim—

1. The method of cooling a gas, consisting in compressing the gas, removing the heat of compression, and then causing the gas to become lowered in temperature by expanding 95 directly against a counter-resisting liquid piston, and using such expanded and cooled gas to cool a further body of compressed gas, and then causing the latter to pass through the same cycle of operation. 100

2. The method of cooling a gas, consisting in compressing the gas, removing the heat of compression, and then causing the gas to do mechanical work by expanding directly 105 against a piston consisting of the same gas liquefied, while insulating the said gas and liquid against external heat.

3. In the process of cooling a gas by causing it under pressure to do work expansively in lifting a column of liquid and allowing the 110 elevated liquid to gravitate to its original level for continued use, the method of preventing such descent from generating heat, consisting in causing the gravitational energy of the liquid to pass off in the form of external work instead of becoming converted into heat. 115

4. The method of liquefying gas, consisting in compressing and cooling the gas, then causing it to do mechanical work by expanding directly against a piston of liquid and elevating the same until expansion has taken place, returning the expanded gas for further compression while utilizing it to cool a further quantity of compressed and cooled gas 120 prior to expansion of the latter, and continuing such cycle of operation till liquefaction of the gas ensues.

5. The method of liquefying gas, which consists in compressing and cooling the gas, then causing it to expand against and in contact with a vertical column of vaporizable liquid, then separating the gas and liquid, returning the cooled gas to the compressor and utilizing 125 130

it in its return to absorb heat from the non-expanded compressed gas, causing the liquid to gravitate to its original level and in its descent to do mechanical work, repeating the 5 above cycle and supplying new gas to the compressor according to the demands of the system.

6. The method of liquefying air, consisting in compressing and cooling the air, then lowering its temperature farther by conduction in a suitable counter-current apparatus, and then causing the compressed and supercooled

air to do mechanical work by expanding directly against a piston of liquid air.

7. The method of liquefying air consisting 15 in causing air which has been first compressed and cooled to expand against a body of liquefied air within a heat-insulated vessel.

Signed at Washington, in the District of Columbia, this 29th day of August, A. D. 1899. 20
